Inventor,

Thomas D. Wilkinson

UNITED STATES PATENT OFFICE.

THOMAS D. WILKINSON, OF PORTLAND, MAINE.

TELEGRAPH-WIRE JOINT.

SPECIFICATION forming part of Letters Patent No. 635,007, dated October 17, 1899.

Application filed April 25, 1899, Serial No. 714,375. (No model.)

To all whom it may concern:

Be it known that I, THOMAS D. WILKINSON, residing at Portland, in the county of Cumberland and State of Maine, have invented 5 certain Improvements in Telegraph-Wire Joints, of which the following is a specification.

The present invention relates to telegraph-wire joints and to a specially-prepared connector by means of which the ends of the wires are joined to each other and belongs to that class of sheath-connectors consisting of one or two tubes of metal, into the opposite ends of which the line-wires are inserted and 15 then the whole twisted together. In all such connectors that I am aware of the ends of the wires project through the ends of the tubes and are sometimes bent or turned to one side, and in all such devices a square sharp shoulder exists where the wire projects through the tubes, which is a serious disadvantage when the connected wire is drawn along over cross-arms and other supports, as the shoulder catches upon them, and in order to free 25 the same the wire has to be jumped or jerked, which causes it to bend near the shoulder and in a short time develops a fracture.

The present invention aims to provide a construction whereby the connected wires 30 can be evenly and smoothly drawn over all obstructions and also whereby a more perfect electrical contact is maintained between the wires and the enveloping sheath, all of which I will now proceed to describe and 35 claim, reference being had to the accompanying drawings, in which—

Figure 1 represents a wire-connector of the usual construction. Fig. 2 represents a wire-connector embodying my invention. Fig. 3 40 is a longitudinal section of the same before it is twisted. Figs. 4, 5, 6, and 7 show one construction of the wire-connector and method of forming the same. Figs. 8 and 9 illustrate a second construction and method of forming 45 the same. Figs. 10 and 11 show a third form of wire-connector, and Fig. 12 represents a fourth construction of wire-connector.

Fig. 1 shows the common form of double-tube copper-wire connector *a*, having square 50 ends, with a line-wire *w* inserted into one tube and projecting through the opposite end, and *w*² is the second line-wire inserted into

the lower tube at the diagonal corner of the opposite end and projecting through the tube. Now when the connected wire is drawn along 55 across or over the cross-arms or other supports the shoulders *s* catch upon the corners thereof and stop its progress, so that the wire has to be jerked, producing a bend at its junction with the tubing *a*, as shown in 60 dotted lines, and in a short time a fracture is developed which ends in a break, causing serious loss and damage.

Fig. 2 illustrates my invention, which consists in providing a connector which holds 65 the wires in a parallel position as firmly and securely as in the old construction and with a curving or tapering shoulder *S* at each of the diagonal corners of the opposite ends of the tubes, with their sides rounded to conform in cross-section to the tubes, whereby 70 the connected line-wire can be drawn over the edges and corners of any support without the liability of its catching.

Figs. 3, 4, 5, 6, and 7 illustrate a construction by which such a curving or sloping shoulder is produced. The connector is made of two tubes *c* and *d* of the same diameter and length, secured to each other longitudinally by soldering or brazing. Each tube has one 80 end *e* brought to a point by spinning it down in a manner well understood, as shown in Fig. 6. The tubes are placed as shown in said figure and brazed together, at which time (or before, if thought best) the point *e* is forced 85 to one side and brazed to the end of the opposite tube, as shown in Fig. 7, and when thus completed there is provided a connector having two parallel tubes closed at their opposite ends, which ends are provided with 90 curving or tapering shoulders.

Figs. 8 and 9 show another means for closing the ends of the tubes. In the former figure a tube *c* is slipped over a mandrel *f*, which is then inserted between the open dies *g* and 95 *h*, the upper one *g* being semicircular in cross-section, and when it is brought down upon the end of the tube it compresses and crumples the metal into a thick end, as shown in Fig. 9. Tubes thus formed are then brazed 100 to each other.

In Figs. 10 and 11 the connecting-sheath *a* is of one tube having its opposite ends *S S* compressed, so that the openings at each end

are of the size of the line-wire, into which the wires are inserted and the whole twisted.

Fig. 12 shows another means for closing the end of a tube and forming a tapering end. A 5 solid piece of metal *i* of the proper shape is cast or otherwise produced having a reduced or shouldered end which extends into the tube and is then soldered or brazed in.

By means of these constructions a very superior connector is formed, as the closure of 10 one end of each tube reduces the chance of moisture entering the connector one-half, and therefore a much better contact and of the least possible resistance is produced.

15 I claim as my invention—

1. A telegraph-wire connector consisting of two integral parallel tubes, the diagonal opposite ends of which are closed and having curving or tapering surfaces, as set forth.

2. A telegraph-wire connector consisting of 20 two parallel tubes brazed to each other, the diagonal opposite ends of which are closed or solid and having curved or tapered surfaces, as set forth.

3. The combination in a twisted telegraph-wire joint of two telegraph-wires with a connector consisting of two parallel tubes the diagonal opposite ends of which are closed and having curved or tapered shoulders, as set forth. 25

In testimony whereof I have signed my name to this specification, in the presence of two subscribing witnesses, this 19th day of April, 1899. 30

THOMAS D. WILKINSON.
